UNITED STATES PATENT OFFICE.

HENRY J. PAULSEN, OF LOS ANGELES, CALIFORNIA.

BOTTLE-FILLING APPARATUS.

1,413,772.

Specification of Letters Patent. Patented Apr. 25, 1922.

Application filed July 6, 1920. Serial No. 394,342.

To all whom it may concern:

Be it known that I, HENRY J. PAULSEN, a citizen of the United States, residing at Los Angeles, in the county of Los Angeles, State 5 of California, have invented a new and useful Bottle-Filling Apparatus, of which the following is a specification.

My invention relates to bottle filling apparatus being more particularly of the type 10 known as vacuum apparatus for filling bottles with various forms of liquids.

The principal object of my invention is to produce an apparatus of the class described of simple form and construction, of neat 15 design and simple and economical operation.

The other objects and advantages will appear here and after in the following description.

Referring to the drawings which are for 20 illustrative purposes only:

Fig. 1 is a side elevation of an apparatus embodying a form of my invention.

Fig. 2 is a side elevation partly in section of the upper portion of the apparatus shown 25 in Fig. 1.

Fig. 3 is an enlarged side elevation of the top of the apparatus looking in the opposite direction to Fig. 2.

Fig. 4 is a plan view of the apparatus 30 shown in Fig. 3.

Fig. 5 is an enlarged vertical sectional view of the filling head.

Fig. 6 is a sectional plan view on line 6—6, Fig. 5.

35 11 designates a base upon which is mounted an exhauster 12 driven by means of a belt 13 from a motor 14.

15 designates a closed tank mounted upon a base 11 having a flanged head 16.

40 Mounted upon the head 16 by means of suitable standards 17 is a head plate 18 provided on its upper face with a rib 19 terminating at its inner end in a shoulder 20. The under face of the plate 18 is provided with a circular

45 groove 22 in which is placed a rubber gasket 23 for the purpose of receiving the neck 24 of a jar 25 preferably formed of glass or similar transparent material. Such jar being held and suspended on the under 50 side of the plate 18 by means of a common form of bail 26 which engages over the rib 19 and against the shoulder 20.

The exhauster 12 is connected to the tank 15 by means of suitable piping 27. 28 designates a pipe connected into the upper end of the tank 15, such pipe being connected by a

fitting 29 to a pipe 30, which, in turn, is connected by a fitting 31 to a pipe 32, such pipe 32 being provided with a valve 33 connected into the plate 18, such valve 33 opening into the interior of the jar 25. 35 designates a gage connected to the fitting 31 and 36 designates a drain cock connected to the fitting 29. 40 designates a pipe one end of which is connected by a coupling 41 to a pipe 65 42 in the plate 18, such pipe being in open communication with the interior of the jar 25.

The outer end of the pipe 40 is connected by means of a coupling 44 with a hollow 70 stem 45 formed on the upper end of a hollow head 46. Such stem being provided with a circular flange 47 which engages the upper face of an arm 49 on the plate 18, the lower face of the arm being engaged by the upper 75 face of the head 46 and the stem 45 extending into and fitting within a slot 48 formed in the end of an arm 49, which arm forms part of and extends outwardly from the plate 18.

The hollow head 46, for the purpose of assembling, is formed by two parts, an upper part 50 and a lower part 51. The bottom of the head 46 is provided with a circular hole formed therein through which extends downwardly the end or nozzle 53 of a pipe 54. A portion of the nozzle 53 is grooved, as indicated at 55, thereby forming openings or 80 passages which afford an open communication from the chamber 56, formed in the head 46, and the interior of the bottle to be filled, indicated at 57. The mouth of such bottle is held against a washer or cushion 58 of leather or other suitable material carried on the nozzle 53 and abutting against the under face of the head 46.

It is to be noted that the pipe 54 extends horizontally into the chamber 56 in the head 46 and that the nozzle 53 of the pipe extends at right angles thereto downwardly from the head. In assembling, after such pipe has been placed in the head, the two parts of the head are secured together as one piece by welding or any other suitable manner. The pipe 54 is provided with an enlarged end 105 60 provided with circular grooves 61 over which is secured one end of a flexible hose 63, the other end of the hose extending into the liquid 64 with which the bottles are to be filled, such liquid being contained in a 110 jar or receptacle 65. The outer end of the pipe 54 is provided with a valve casing 67

threaded thereinto, such casing being provided with a ball valve 68 arranged to engage a seat 69 for the purpose hereinafter described.

5 The apparatus operates in the following manner:

The exhauster is operated by the motor for the purpose of exhausting the air in the tank 15, the vacuum obtained in such tank 10 being indicated upon the gage 35. When it is desired to use the apparatus for filling bottles the jar 25 is arranged in place as heretofore described and the valve 33 opened. The jar then being in open communication

15 with the tank 15 a vacuum is obtained in the jar, also in the pipe 40, and the chamber 56 in the head 46. The bottle to be filled is then held against the washer 58 and a vacuum produced in the interior of the bottle 20 through the passages 55 which communicate with the chamber 56 in the head. The vacuum in the bottle unseats the ball 68 thereby producing a vacuum in the pipe or hose 63 which draws the liquid from the container 25 into the bottle 57. When the bottle 57 is filled it is removed from the washer 58 thereby breaking the vacuum causing the ball 69 to be seated, which operation of the ball prevents the liquid in the hose 63 from

30 running back into the container, such action serving a material purpose in the filling operation as when the next bottle is filled it is not necessary to draw the liquid from the container up to the filling head.

35 Further advantage of the arrangement of the pipe 54 is that it extends laterally from the head to the hose 63, at no point being higher than the head. In the event that the bottles are held too long against the filling 40 head liquid will be drawn through the pipe 40 into the glass jar 25, such jar serving as an indicator of such operation and providing a warning so that the drawing over of liquid into the main tank or reservoir 45 may be avoided. It is understood that any liquid accumulating in the jar may be removed readily by unfastening the bail from the plate 18.

The pipe 40 may be made of flexible hose 50 as will readily occur to anyone skilled in the art and the filling head manipulated by hand thus allowing the bottles to be filled to be placed upon a table or other support.

What I claim is:—

55 1. A filling apparatus comprising a filling head having a chamber formed therein, a cushion on the bottom of said head arranged to receive the mouth of a bottle, said cushion having an opening therein, said bottom of 60 the filling head having an opening therein corresponding with the opening in the cushion, a liquid conductor extending through the side wall of said head into said chamber consisting of a single pipe, a nozzle formed 65 on the inner end of said conductor con-

sisting of an extension on said pipe at right angles thereto extending downwardly through the opening in the bottom of said head and the opening in said cushion, said nozzle having longitudinally extending 70 grooves formed in the outer face of said nozzle forming air passages between said chamber and the bottle to be filled, a check valve in said liquid conductor, an air conductor connected to said head in open communication with the chamber in said head, and means for exhausting the air in said chamber through said air conductor.

2. A filling apparatus comprising a filling head having a chamber formed therein, a 80 pipe for liquids extending through the side of said head into said chamber, the inner end of said pipe extending downwardly through the bottom of said head forming a single nozzle, said nozzle having passages 85 formed in its outer face affording open communication from said chamber to the exterior thereof, a check valve in said liquid conductor arranged adjacent to the head, and an air conductor attached to the head in 90 open communication with said chamber.

3. A filling apparatus comprising a head plate, a filling head having a chamber therein supported on said head plate, a liquid pipe extending through the side of said head into said chamber, a nozzle formed by extending the inner end of said pipe downwardly through the bottom of said head, said nozzle having grooves formed in the 95 outer face thereof forming open communication between said chamber and the exterior of said head, an air conductor attached at one end to said head in open communication with the chamber in said head, a jar supported on said plate having the other end of said air conductor in communication with the interior of the jar, a tank, and air connections between said tank and said jar.

4. A filling apparatus comprising a head plate having a slot formed therein, a filling head having a chamber formed therein, a hollow stem on said filling head extending through the slot in the head plate, a flange on said stem arranged to engage said plate and support the filling head thereon, an air conductor connected to said stem, a liquid conductor extending into said chamber through the side of said head, and a nozzle on the inner end of said liquid conductor formed by extending the end of said conductor downwardly through the bottom of said head, said nozzle having slots in the outer face thereof forming passages from said chamber to the exterior of said head.

5. A filling head for bottle filling apparatus comprising a head having a chamber formed therein, a hollow stem on said head forming an air passage in open communication with said chamber, and a pipe extending through the side wall of said head into 130

said chamber, the inner end of said pipe extending downwardly through the bottom of said head, said downwardly extending end having grooves formed in the outer face thereof forming air passages to said chamber.

6. A filling head for bottle filling apparatus comprising a head having a chamber formed therein, a hollow stem on said head forming an air passage in open communication with said chamber, and a pipe extending through the side wall of said head

into said chamber, the inner end of said pipe extending downwardly through the bottom of said head, said inner end having grooves formed in the outer face thereof forming air passages to said chamber, a check valve in said pipe exterior of said head and a liquid conducting tube connected to the outer end of said pipe.

In testimony whereof, I have hereunto set my hand at Los Angeles, California, this 26th day of June, 1920.

HENRY J. PAULSEN.
